(57) CLAIM

We claim the ornamental design for a media player with a camera, as shown and described.

DESCRIPTION

FIG. 1 is a front perspective view of a media player with a camera.

FIG. 2 is a rear perspective view of the media player with a camera illustrated in FIG. 1.

FIG. 3 is a front elevational view of the media player with a camera illustrated in FIG. 1.

FIG. 4 is a rear elevational view of the media player with a camera illustrated in FIG. 1.

FIG. 5 is a right side view of the media player with a camera illustrated in FIG. 1.

FIG. 6 is a left side view of the media player with a camera illustrated in FIG. 1.

FIG. 7 is a top plan view of the media player with a camera illustrated in FIG. 1; and,

FIG. 8 is a bottom plan view of the media player with a camera illustrated in FIG. 1.

The portions of the media player with a camera in broken lines are shown for illustrative purposes only and form no part of the claimed design.
